UNITED STATES PATENT OFFICE.

MATTHEU H. FIELDING, OF ALTON, FLORIDA.

CONTRACTING DRY-KILN TRUCK.

1,125,082.

Specification of Letters Patent. Patented Jan. 19, 1915.

Application filed December 17, 1913. Serial No. 807,333.

To all whom it may concern:

Be it known that I, MATTHEU H. FIELDING, a citizen of the United States of America, residing at Alton, in the county of Lafayette and State of Florida, have invented 5 certain new and useful Improvements in Contracting Dry-Kiln Trucks, of which the following is a specification, reference being had therein to the accompanying drawing.

10 This invention relates to contracting dry kiln trucks and has for its object the production of a simple and efficient truck which will efficiently support green timber so as to prevent the timber from falling from the 15 trucks after the same has become dried.

Another object of this invention is the production of a simple and efficient means for forcing the supporting standards of the trucks toward the center of the trucks in 20 order to keep the timber in a compacted relation after the same has become dried.

With these and other objects in view this invention consists of certain novel combinations, constructions, and arrangements of 25 parts as will be hereinafter fully described and claimed.

In the accompanying drawings:—Figure 1 is a perspective view of the trucks supported upon a section of a track. Fig. 2 is 30 a transverse sectional view through one end of the trucks. Fig. 3 is a side elevation of one of the trucks showing the inner plate removed therefrom. Fig. 4 is a perspective view of one of the side plates of the truck 35 frame. Fig. 5 is an enlarged side elevation of one end of the truck showing the inner plate removed therefrom. Fig. 6 is a section taken on line 6—6, of Fig. 5. Fig. 7 is a perspective view of one of the compressing 40 levers. Fig. 8 is a detail perspective of one end of one of the timber supporting bars. Fig. 9 is a detail perspective of the lower 45 end of one of the timber supporting standards.

By referring to the drawings it will be seen that the present kiln truck comprises a pair of similarly constructed truck frames 1. Each of the truck frames 1 comprises an outer plate 2 and an inner plate 3. Each of 50 the plates 2 and 3 is provided with closed ends 4, and a filler block 5 is interposed between the respective ends of the plates 2 and 3. Compression levers 6 are pivotally mounted between the respective ends of the 55 plates 2 and 3 as shown in Fig. 3.

Supporting wheels 8 are secured to the

trucks 1 by means of the axles 9, which axles extend transversely of the kiln truck to connect the parallel truck beams. The wheels 8 are journaled upon the shaft between the inner and outer plates 2 and 3 as is clearly illustrated in Figs. 2 and 3.

The compression levers 6 comprise substantially L-shape bodies having their inner ends inwardly extending so as to constitute 60 supports for the timber carrying frames or bars 10. These bars 10 are preferably of an I-beam structure having parallel longitudinally extending cleats 11 formed along their upper edge and extending beyond the 65 respective ends of the body of the bars 10 so as to constitute a pocket for the vertically extending compression standards 12. The projecting ends 13 of the cleats 11 straddle the compression levers 6 and constitute guides for these compression levers 70 to normally hold the compression levers in engagement with the standards 12. The lower ends of the standards 12 are notched 75 as indicated at 14 for fitting over the longitudinally extending rib portions 15 formed upon the inner and outer plates 2 and 3. It will, therefore, be seen that the standards 12 80 will be held against removal from the trucks 1, in view of the fact that an enlarged head 85 16 has been produced by forming the notched portions 14 in the standards 12.

A cam 17 is carried at each end of each of the trucks 1 and is adapted to engage the under face of the inwardly extending portion 18 of the compression levers 6 to hold the levers in a set position while loading the truck. Locking bolts 19 pass transversely through the inner and outer plates 3 and 4 of the trucks 1 as illustrated in Fig. 90 6 and are adapted to extend through the cams 17 to hold the cams in a set position 95 and prevent the free operation of the compression levers 6. These bolts 19 are provided with squared heads 20 for the purpose of facilitating the operation of the bolts. After the truck has once been loaded the cams 17 may be removed from the levers 6 thereby allowing the cams 17 to swing 100 downwardly and permit the free swinging of the clamping levers 6 as the green timber placed upon the frame or bars 10 contracts as the timber becomes dried.

From the foregoing description it will be seen that a very simple and efficient means 110 has been produced for supporting green timber upon a truck and causing the timber

to be held in a compacted relation while the same is in the process of being dried. By means of the present invention it will be seen that the timber may be piled or stacked upon the several trucks and the timber will at all times maintain its proper relation owing to the fact that as the timber contracts the weight of the timber will press upon the inwardly extending portions 18 of the lever 10 and since the resistance to the vertically extending portions 21 of the lever 6 will be lessened, the standards 12 will be forced inwardly so as to hold the timber in its correct or desired relation. Of course, it should be understood that the timber may be placed upon the trucks in any desired manner, but it is preferable to place the timber upon the trucks by piling the same edgewise and placing special cleats between each pile to allow 20 a free circulation of heat or air between the several rows of timber.

Having thus described the invention what is claimed as new, is:—

1. A device of the class described comprising a plurality of truck frames, an article supporting member carried by each frame, pivoted compression means carried by each truck frame and supporting said article supporting member and adapted to 30 compress an article carried by the article supporting member when the article shrinks.

2. A dry kiln truck comprising a plurality of truck frames, timber supporting members vertically movable within said truck frames, angle levers carried by said truck frames and provided with inwardly extending ends, said timber supporting members supported by said inwardly extending ends of said angle levers for causing the upper 40 ends of said angle levers to be forced inwardly by means of the weight of the timber upon said timber supporting members as the timber supported thereby shrinks.

3. A truck of the class described comprising a plurality of elongated truck frames having upper and lower side flanges, a timber supporting member of a substantially I-beam structure supported thereby and vertically movable therein, angle levers provided with inwardly extending ends, said timber supporting members supported upon said inwardly extending ends, said angle levers provided with upwardly extending ends adapted to be forced inwardly as the

timber supported by said timber supporting members shrink, and means for holding said angle levers in a set position.

4. A device of the class described comprising a truck, a timber supporting member vertically movable upon said truck, an angle member carried by said truck and provided with an inwardly extending end supporting said article supporting member, a cam adapted to fit under said inwardly extending end for holding said angle lever in a set position, 60 and a rotatable bolt passing through said truck and engaging said cam for holding said cam in a set position.

5. A device of the class described comprising a truck formed of a plurality of plates, 70 a vertically movable timber supporting member carried thereby and provided with a pair of side cleats having projecting ends, standards positioned within said projecting ends of said side cleats, angle levers fitting 75 in between said projecting ends, said projecting ends constituting guides for holding said standards and angle levers in their correct position, and means formed upon said standards for preventing the vertical 80 displacement thereof from said truck.

6. A truck of the class described comprising a body, an article supporting member, said article supporting member provided with bifurcated ends, vertical standards, said 85 truck provided with side plates having inwardly extending flanges along the upper edge thereof, said standards provided with notches formed therein, said notches fitting over said flanges of said side plates of said 90 truck, angle levers pivotally mounted upon said truck and provided with inwardly extending ends supporting said article supporting member, said angle levers provided with upwardly extending ends engaging 95 said standards and adapted to force the same inwardly as the timber carried by said article supporting member contracts, the weight of said article supporting member and said timber constituting means for causing the upper ends of said angle levers to be swung inwardly.

In testimony whereof I hereunto affix my signature in presence of two witnesses.

MATTHEU H. FIELDING.
